ness as Premier Gem Company, New York,
N. Y.

Application March 25, 1952, Serial No. 19,048

Term of patent 14 years

(Cl. D17—7)

To all whom it may concern:

Be it known that I, Philip Colmar, a citizen of the United States and a resident of the city of New York, county of Queens, State of New York, have invented a new, original, and ornamental Design for a Cuff Link or Similar Article, of which the following is a specification, reference being had to the accompanying drawing constituting a part thereof in which:

Fig. 1 is a plan view of a cuff link or similar article, showing my new design.

Fig. 2 is a longitudinally sectional view through

2—2 of Fig. 1.

Fig. 3 is a transversely sectional view through 3—3 of Fig. 2.

The dominant features of the design reside in the portions shown in full lines.

I claim:

The ornamental design for a cuff link or similar article, substantially as shown and described.

PHILIP COLMAR.
